UNITED STATES PATENT OFFICE

JOHN B. HOLTZ, OF LOS ANGELES, CALIFORNIA, ASSIGNOR TO INVENTION DEVELOPMENT CORPORATION, OF CARSON CITY, NEVADA

DESIGN FOR AN ADVERTISING PEDESTAL FOR WEIGHING MACHINE

Application filed July 29, 1929. Serial No. 32,238. Term of patent 3½ years.

To all whom it may concern:

Be it known that I, JOHN B. HOLTZ, a citizen of the United States, and a resident of Los Angeles, Los Angeles County, California, have invented a new, original, and ornamental Design for Advertising Pedestal for Weighing Machine, of which the following is a specification, reference being had to the accompanying drawing, forming a part hereof.

In the drawing, the figure is a front per-

spective view of an advertising pedestal for weighing machine embodying my invention.

The upright column portion of the design is substantially circular in cross section, while the top is of circular disc like form having a relatively short axial dimension.

I claim:

The ornamental design for an advertising pedestal for weighing machine, substantially as shown and described.

JOHN B. HOLTZ.
